UNITED STATES PATENT OFFICE.

EDWIN L. WHITE, OF NEW YORK, N. Y., AND WILLIAM M. GILBERT, OF WATERBURY, CONNECTICUT, ASSIGNORS TO GEORGE H. CLOWES, OF WATERBURY, CONNECTICUT.

HOLDER FOR CALCIUM CARBID.

SPECIFICATION forming part of Letters Patent No. 645,152, dated March 13, 1900.

Application filed April 28, 1898. Serial No. 679,082. (No model.)

To all whom it may concern:

Be it known that we, EDWIN L. WHITE, residing at New York, (Brooklyn,) in the county of Kings and State of New York, and WILLIAM M. GILBERT, residing at Waterbury, county of New Haven, State of Connecticut, citizens of the United States, have invented certain new and useful Improvements in Holders for Calcium Carbid, of which the following is a specification, reference being had therein to the accompanying drawings.

Our invention relates to receptacles for holding calcium carbid of such a character that they can be rendered air and moisture tight for holding the material preparatory to its use in a lamp burning acetylene gas, can be placed in the generating-chamber of such a lamp and utilized for the generation of gas until all of the carbid therein is exhausted, and can then be removed with its contents, the resultant lime, and thrown away.

The object of our invention is to provide a receptacle of this nature which can be manufactured at a slight cost, which can be quickly charged with a given quantity of carbid and then securely sealed against air and moisture, which will hold the carbid therein in a compact mass, which is not liable to be disturbed by movement or jolting of the receptacle, and which will contain means for evenly distributing water admitted to said receptacle to said mass in such manner as to produce an even and regular generation of gas until all of the carbid has been utilized.

To these ends our invention consists in the receptacle constructed and operating as hereinafter fully described, and particularly pointed out in the claims.

Referring to the drawings, in which like numerals designate like parts in the several views, Figure 1 is a vertical section of a receptacle embodying our invention. Fig. 2 is a plan view thereof with the cover or cap removed. Fig. 3 is a partial vertical section of a slightly-modified form of receptacle embodying the invention.

As shown in Figs. 1 and 2, the numeral 1 designates the body of the receptacle, which is preferably of circular form, as shown, said body containing a lining 2, which engages

the inner side of the vertical wall thereof and projects above said wall to the top of the receptacle, and 3 designates a cover or cap which closely fits over said lining and rests upon said body 1 to close the receptacle. 55 Upon the bottom of the body 1 rests a disk 4, having a centrally-located circular opening, into which projects the lower end of a tubular core 5, which core extends to the top of the receptacle and is thus maintained in a 60 central position therein. An annular chamber 6 is thus formed between the core 5 and the lining 2, within which is placed the calcium carbid, as represented in Fig. 1, the same being preferably in loose form—that is 65 to say, not formed into a hardened cake. Above the carbid is a disk 7, having an opening to receive the core 5, whereby it is adapted to be pressed down upon the carbid and to be retained in such position by its frictional 70 engagement with the lining 2. The opening in said disk 7 is of slightly-greater diameter than that of the core 5, thus affording sufficient space to permit the escape of the gas when generated. The cover 3 has a central 75 opening 8, which is normally sealed by an easy-puncturable sheet 9 of paper or other suitable material pasted to the inner side of the cover and closing said opening.

The receptacle thus constructed is preferably composed of paper-board or similar cheap material, and it is used as follows: After the desired quantity of carbid has been placed in the annular chamber 6 and the disk 7 has been forced down upon the same the cover 3 is applied to the body 1, and the line of juncture between the body and cover is sealed by covering the same with a strip of paper and coating it with a suitable waterproof material—such, for example, as paraffin. The receptacle and its contents are then ready to be sold as an article of manufacture. To apply the receptacle to a lamp, it is placed in the generating-chamber thereof, and the drip-tube, which conducts water from the water-reservoir to said chamber, is thrust through the sealing-strip 9, as represented by broken lines in Fig. 1. The lamp is now ready for use, and as soon as the valve governing the flow of water through said drip-tube is opened the 100

water thus admitted to the interior of core 5 permeates the wall thereof and, moistening the carbid, causes the latter to begin its generation of gas, the latter escaping through the 5 space between the core and disk 7 and through the opening 8 in the cap around the drip-tube. Such operation continues until the supply of water is shut off or until the gas-producing properties of the carbid have been exhausted, 10 the receptacle in the latter case being withdrawn from the lamp and thrown away and a new receptacle substituted therefor.

The carbid being confined within the annular space 6, as described, is prevented from 15 movement however much the receptacle may be jolted, and the water being fed thereto in an even and regular manner through the core 5 an even and steady flame at the burner is assured at all times, thus rendering our receptacle particularly applicable to bicycle-lamps, in which great difficulty has been encountered heretofore in securing a steady flame, because of the irregular application of the water to the carbid due to the jolting 25 movement of the lamp, such movement bringing moist particles of the carbid into contact with dry particles and causing a sudden accession to the body of gas generated. The carbid being thus placed in an air and moisture proof receptacle is in convenient form to 30 be marketed and to be carried about the person or in the tool-bag of a bicycle-rider, for example, ready for use when needed. It can be readily placed in and removed from the 35 lamp, the resultant lime being removed with it, thus preventing the lamp-chamber from becoming fouled from such cause.

As before stated, we prefer to form the receptacle from paper-board or other similar 40 material; but, if desired, the body and its cover can be made of tin or other sheet metal, and in Fig. 3 we have shown a portion of a body 10 so formed. In this case instead of using a disk 4 at the bottom of said body to 45 form a joint with the lower end of the core the bottom of said body has a centrally-located raised projection 12, which is adapted

to closely fit within the lower end of said core and which tapers slightly from its center to its circular edge to facilitate guiding the water to the inner surface of the core. In lieu of said raised projection said bottom could be provided with a central depression of the proper diameter to receive the end of the core with substantially the same result. The 55 core 5 also instead of being formed from an absorbent material such as we have described could be made from metal or other non-absorbent material, with perforations therein to permit the passage of water therethrough, 60 as represented by the core 13 in Fig. 3; but as these modifications increase the cost of the receptacle without increasing its efficiency we prefer to make it as first described.

Various other modifications coming within 65 the scope of our invention will suggest themselves to persons skilled in the art.

Having thus fully described our invention, what we claim, and desire to secure by Letters Patent, is—

1. A receptacle consisting of a body having an annular chamber for holding calcium carbid, a centrally-located, tubular core extending upwardly from the bottom thereof, and an annular disk surrounding said core which 75 is adapted to rest upon the carbid in said chamber, and to retain its position thereon while the said carbid is expanding, said body having a removable cover which is provided with a central opening, said opening being 80 closed by an easily-punctured closure, substantially as described.

2. A receptacle comprising the body 1 having the lining 2, tubular core 5, and disks 4 and 7, and the cover 3 having the opening 8 and easily-punctured closure 9, substantially as set forth.

In testimony whereof we affix our signatures in presence of two witnesses.

EDWIN L. WHITE.

WILLIAM M. GILBERT.
